UNITED STATES PATENT OFFICE.

EDWIN C. HENN, OF CLEVELAND, OHIO, ASSIGNOR TO THE NATIONAL-ACME MANUFACTURING COMPANY, OF CLEVELAND, OHIO, A CORPORATION OF OHIO.

METAL-WORKING MACHINE.

1,005,833.

Specification of Letters Patent.

Patented Oct. 17, 1911.

Application filed September 30, 1910. Serial No. 584,602.

To all whom it may concern:

Be it known that I, EDWIN C. HENN, a citizen of the United States, residing at Cleveland, in the county of Cuyahoga and State of Ohio, have invented certain new and useful Improvements in Metal-Working Machines, of which the following is a specification.

This invention relates to metal working machines, more particularly to that class thereof known as automatic multiple spindle screw machines, the object of the invention being to provide an improved machine of this character by means of which the successive threading of the rod spindles may be accomplished much more quickly than heretofore by reason of the fact that the work or rod spindle is, during the threading of the rod by the threading die, held stationary, while the backing off of the die is obtained without the necessity of starting up or rotating the work spindle or reversing the threading die.

A further object of the invention is the provision of an improved metal working machine in which the work spindle and its threaded rod may be quickly released from the threading die and rotated immediately after the thread has been cut, without the necessity of waiting, as heretofore, until the cutting or threading die has been backed off, thus materially increasing the output of the machine while accomplishing this procedure in a very simple and effective manner.

A further object of the invention is the provision of an improved machine in which the threading die does not need to be stopped, and therefore may be continuously rotated in the same direction both during the threading of the work and the backing off of the die therefrom, while the direction of rotation of the work or rod likewise does not need to be reversed.

In the drawings accompanying and forming part of this specification, Figure 1 is a perspective view of an automatic multiple spindle screw machine embodying the present improvement; Fig. 2 is an end view of the machine with parts thereof in section and broken away, looking from right to left in Fig. 1; Fig. 3 is a side elevation of the work spindle end of the machine shown in Fig. 2; Figs. 4 and 5 are partly longitudinal sectional views illustrating the threading die

in different positions; Fig. 6 illustrates a modification of the threading die opening means shown in Figs. 1 to 5; Fig. 7 is a detail view more particularly illustrating the threading die and the means for operating it; Fig. 8 is a detail view, partly in section, of the threading die and its spindle; Fig. 9 is an end elevation, with parts thereof broken away, of the threading die; Fig. 10 is a cross sectional view of the threading die; and Figs. 11 and 12 are respectively a sectional and a perspective view of a form of clutch for holding the work spindle stationary during the threading operation.

Similar characters of reference indicate corresponding parts throughout the figures of the drawings.

In the preferred form thereof herein shown, the several parts of the machine are mounted upon a suitable bed 2 carrying a cam shaft 3 on which are mounted cam drums 4 and 5, one of which, as 4, controls the sliding movement of the sliding tool head or carrier 6 carrying a series of tools, each mounted in a spindle. Supported upon the bed is a turret casing 7 carrying a revoluble work turret 8, which is rotated in some suitable manner through the medium of the cam shaft 3. This revoluble turret carries a series of work or rod spindles 9, which spindles are rotatable by suitable mechanism. Only a general description of these parts is deemed necessary, since they are well known.

For the purpose of threading each rod successively as it is brought into position opposite the threading die hereinafter described, an improved threading mechanism is provided, the threading operation being carried on on a stopped or stationary work spindle, and for the purpose of stopping and holding the spindle stationary during this threading operation some suitable form of mechanism is provided. This may include a clutch mechanism either friction held for stopping the spindle or positively locked means. In the present improvement the mechanism shown for that purpose, and for operating it, is similar in part to that shown and described in the application of Oscar A. Smith, Serial No. 571,955, filed July 14, 1910, and therefore only a general description thereof is deemed necessary herein. This mechanism is located in position to cooperate with each rod spindle as it is suc-

cessively carried into position to have the work carried thereby operated upon by a threading die, for the purpose of stopping the rotation of the spindle, which is normally rotating, during the threading operation and to permit the continued rotation of the work spindle after such threading is completed. Each rod spindle, four being shown herein, is provided with a suitable friction clutch mechanism 10, see Figs. 11 and 12. Each of these clutch mechanisms comprises a cone clutch 12 loosely mounted on the spindle shaft 12' and carrying a gear 10' which is continuously rotated by the usual gear provided for that purpose. Co-operating with the coned end of this clutch member 12 is a clutch sleeve 11 maintained in frictional engagement with the member 12 of the clutch by means of spiral springs 9'. One end of each spring is in engagement with the shiftable clutch member 11 while the opposite end of the spring engages a collar 13 slidable on the spindle shaft and shifts it toward and from a fixed collar 14 fixedly secured to the shaft, whereby when the clutch sleeve 11 is shifted away from the clutch member 12 the springs 9' will force the collar 13 into engagement with the collar 14 and thus, by this frictional engagement, hold the spindle shaft against rotation. The clutch member 11 is keyed to a sleeve 11', which is fast to the spindle shaft 12', whereby when the clutch members 11 and 12 are in engagement the rotation of the clutch member 12 by means of the gear 10' will rotate the spindle shaft. The friction engaging means just described may be used for holding the spindle shaft stationary for some forms of work, as for instance light work. For heavier work, however, it is desirable to have a positively acting means for preventing the rotation of the spindle shaft, and thereby the work, during the threading operation, and for this purpose the bracket 15 hereinafter described is provided with a spring actuated pin 50 adapted to engage projections 51 carried by the clutch member 11, the spring 52 being useful to permit the pin to be moved out of the way temporarily should the ends of the projections 51 contact therewith when the clutch member 11 is shifted. It will be observed that when the clutch member 11 is shifted away from the clutch member 12 further rotation thereof will not only be stopped, but the rotation of the shaft to which this clutch member 11 is keyed is prevented. When the clutch operating mechanism is again operated to shift the clutch member 11 into engagement with the clutch member 12 the member 11 is carried away from the pin 50, and consequently the spindle shaft will be then rotated.

For the purpose of separating the clutch members 11 and 12 and holding them out of

engagement, and for which purpose it is essential to compress the springs 9', friction clutch operating mechanism is provided. This comprises a bracket 15 rigidly secured to the turret casing 7 and carrying a shaft 16, on which is mounted a pair of levers 17 having projections or rolls 18 adapted to engage the shiftable member 11 of the clutch and shift it against the action of its springs away from its companion clutch member 12. Carried by this shaft 16, at one end thereof, is a bevel gear 19 in mesh with a crown gear 20 mounted on the upper end of a shaft 21, which shaft is suitably supported in bearings carried by a bracket 22 mounted on the bed of the machine. Keyed to this shaft 21 is a crank lever 23 adapted to be shifted into different positions by suitable cam mechanism, thereby to partially rotate the crown gear and so rotate the bevel gear and shift the levers 17 into position either to separate the clutch members or to permit their engagement at the proper time.

The means for shifting the crank lever 23 comprises a cam slide actuated by the cam drum 5. A boss or bracket 24 is located at right angles to the turret casing 7 and is provided with a semi-circular opening into which is fitted to slide easily a semi-circular slide 27 having at its outer end a slotted or bifurcated head 28. On this slide 27 is mounted a cam 29, this being fastened to the flat or upper surface of the slide 27 and resting on top of the boss or bracket 24, the latter being suitably machined to form a proper sliding bearing for the cam 29. On the free end of the crank lever 23 is a suitable friction roll 23' in position to be operated by the cam 29, for which purpose the latter is provided with a slot or recess 30, see Fig. 1, one wall of which, as 31, projects beyond the side face 32 of the cam. In a crotch bearing 33 carried by the bed 2 is hung an actuating lever 34, the upper end of which fits into the slotted head of the slide 27, while the lower end is provided with a roll 35 for engagement with a pair of cams 36 and 37 secured to the cam drum 5 on the cam shaft 3, the cam 36 being effective to operate the lever in one direction while the cam 37 is effective to operate it in the opposite direction. By this improved mechanism that particular friction clutch carried by the rod spindle with which the threading die is intended to co-operate may be opened or released until it is desired to close it again. In other words, as the work or rod spindles carried by the revoluble work turret are successively brought into position to have the clutch members thereof adjacent to the levers or arms 17 of this clutch operating mechanism this mechanism will be operated to release the clutch members and so prevent further rotation of the rod spindle, which is normally ro-

tating, and thus permit the threading of the rod while such work or rod spindle is stationary. In other words, when the cam drum 5, traveling in the direction of the arrow Fig. 2, carries the cam 36 into position to engage the roll 35 of the lever 34 it throws the upper end of this lever inwardly toward the turret casing and so shifts the slide 27 and thereby the cam 29 into position to have the side face 32 of this cam engage and shift the crank lever 23 from one position to another, where it is held against further movement, thereby shifting the shaft 21 and partially rotating the crown gear 15 mounted thereon and consequently rotating the bevel gear 19, which in turn shifts the lever arms 17 mounted on the shaft 16 into position to engage the shiftable member 11 of the friction clutch mechanism 20 and move it against the action of its springs out of engagement with its companion clutch member 12, thus preventing further rotation of the rod spindle, at which time the rod spindle will be held stationary for the 25 operation of the threading die by the friction collars 13 and 14 hereinbefore described, or by the positively acting pin and projections 50 and 51 hereinbefore described.

During the threading operation the cam 30 37 of the cam drum 5 is shifted so that on the completion of such threading it will be in position to engage the roll 35 of the lever 34 and shift the lower end of this lever inwardly and the upper end thereof outwardly, thereby reversing the movement of the cam slide 29 and so carrying such slide away from its locking position and into position to have the projecting portion 31 thereof engage the friction roll 23' of the 35 crank lever 23 and shift such lever with the slide, thereby reversing the crown gear and the bevel gear and thus carrying the arms 17 away from the clutch member 11 and into position where such arms will not interfere 40 with the proper rotation of the turret and spindle, at which time the springs 9' will force the clutch member 11 into engagement with the clutch member 12, whereupon the rod spindle will be again rotated in the 45 manner hereinbefore described. In the present machine the turret casing is shown cut away, as at 60, to permit the proper shifting of the lever arms 17 out of the way in the manner indicated.

50 One of the tools carried by the sliding tool carrier is a threading die 69 adapted to operate successively on the rods carried by the work spindles of the revoluble turret as each is brought into position opposite this threading die, at which time the rotation of the work spindle is stopped by the clutch shifting means hereinbefore described. As the threading die is shown and described in my contemporaneously pending 55 application, Serial No. 543,028, filed Feb-

ruary 10, 1910, only a general description thereof is deemed necessary herein. The threading die comprises a die body 70 having four guides or ways 71 extending radially of the body, the rear portions of which ways are undercut, and in these guideways slide carriers 72 having extensions which slide in the undercut portions of the ways for retaining the carriers therein. Each of these slides has a projecting pin 73 which engages a coiled spring 74 placed in a bore 75 of the die body. These springs tend to shift the carriers outwardly from the axis of the body. In each of these carriers is secured a chaser 76, which may be secured therein by a screw 77. Suitable means is provided for causing the die carriers, and thereby the chasers, to simultaneously advance toward the center or axis of the die, thereby compressing the springs, such compressed springs at the proper time re-acting to shift the carriers outwardly from the axis of the body and thereby open the die. Each of the die carriers is shown provided with a tapered cam surface 78 on its outer portion. Coöperating with each of these cam surfaces is a pin 79 secured in a suitable bore of the die head 80. This die head comprises a flanged sleeve 81 having a groove 81' and a shell or cap 82, the latter 90 inclosing the die body and chasers. The groove 81' formed by the sleeve 81 is adapted to receive a suitable operating device for opening and closing the die. The springs 74 act to press the die carriers outwardly and thereby cause the engagement of the coöperating cam surfaces formed by the tapered portions of the carriers and the cam pins. When the die head is moved forward the pins 79 coöperate with the tapered cam surfaces 78 and press the carriers simultaneously inward toward the center or axis of the die and thus into their closed position, see Fig. 10. When the head is shifted in the opposite direction, or rearwardly, the cam surfaces coöperate to permit the springs to press the carriers outwardly and thereby open the die.

Adjustable means is provided for limiting the inward movement of the die chasers and their carriers, this consisting of a screw 85 working in a threaded bore of the die body, its inner end abutting against the shell 82 and limiting the closing movement of the die body and head. The surfaces 78 of the carriers engaged by the cam pins 79 are made on a slight taper, whereby a very fine adjustment of the die chasers relative to the work can be obtained. Means is also provided for limiting the opening movement of the head and die body, and this consists of a bolt 87 passing through a bore in the die body and seated in a threaded hole of the head, and by this means the separating movement of the head and die 130

body is limited. The threading die is mounted in the usual manner in a die holder 88 carried by a continuously rotating spindle 88' mounted in the sliding tool carrier, see Fig. 8, and rotary movement is imparted thereto by a train of gears 89 from the work spindle driving shaft 90 of the machine.

For opening the die after the threading operation and thereby to permit the die to be backed off without interrupting the rotation thereof and without starting up the work spindle for this purpose, suitable means is provided. In one form thereof it comprises a forked lever 91 fitting into the groove of the die head 80 and fastened by means of a set screw 92 to a shiftable shaft or rod 93 supported in a horizontal bearing 93' of a bracket 94 secured to the tool slide and therefore movable therewith. For shifting this rod or shaft 93 a cam lever 95 is pivoted to the bed of the machine and carries on its lower end a stud and roll 96 co-operating with a tripping cam 98 secured to the cam drum 4, which revolves in the direction indicated by the arrow Fig. 1. On the end of the shiftable shaft or rod 93 is secured a lever engaging stop or projection in the form of an adjustable collar 99, by means of a set screw.

30. In operation, when the lower end of the lever 95 is thrown to the right, the upper end thereof will engage the collar just described and thereby shift the shaft or rod and the forked lever carried thereby toward the left, thereupon carrying the die head into position to permit the co-operating cam surfaces of the die body and head to release the carriers and permit the springs to open the die chasers in the manner hereinbefore described.

In Fig. 6 a somewhat different form of die opening means is provided. In this construction the lever 95 and its co-operating parts are dispensed with. The collar 99 is moved along the shaft 93 so that the space between the collar and the end of the horizontal bearing of the bracket 94 is equal to the length of the thread to be cut minus the lead of the cam. In this form of die opening means the die, during the cutting operation, will carry the shaft 93 forward faster than the travel of the bracket 94 with the tool slide, bringing the collar 99 into contact with the end of the horizontal bearing of the bracket 94, whereupon the travel of the shaft 93, and therefore the clutch lever and the die head will be retarded, thereby releasing the die chasers through the medium of the springs as hereinbefore explained. 60. After the die has been tripped and released or opened, which occurs as soon as the threading operation is completed, it is backed off from the work so that as soon as the die is opened the work spindle can be immediately rotated and the turret indexed to bring an-

other rod into position to be threaded, thus avoiding the necessity of waiting, as heretofore, a considerable period of time for the backing off of the die when this is accomplished by rotating the work relatively to the die or reversing the die.

For closing the die after it has been tripped or released into position to thread another rod, the die spindle is provided with a grooved collar or spool 100 at its outer end. Coöoperating with this grooved collar is a lever 101 having for this purpose a stud roller 102. This lever is pivoted on a bracket 103 movable with the tool slide. This lever carries on its lower end an adjustable screw stop 104 which comes into contact with an adjustable bunter or stop 105 located on the bed of the machine. When the tools carried by the tool slide have completed their operations this tool slide commences to recede through the medium of a cam 106 on the cam drum 4, thereby withdrawing the tools from their respective cutting positions and so bringing the adjustable stop 104 of the lever 101 into contact with the stop 105, which causes the lever 101 to swing on its pivot, thereby accelerating the movement of the die spindle to the left in the same direction in which the tool slide and the die spindle are traveling. This accelerated movement of the die spindle shifts the die body with relation to the die head or cap, which is prevented from accelerated movement during the receding movement of the tool slide by reason of the fact that the forked lever in engagement with the groove of such die head and carried by the shaft 93 comes into contact at this time with the forward end of the horizontal bearing of the bracket 94 and thus prevents the sleeve or die head from further movement, so that, owing to the accelerated movement of the die body, this body is drawn back into the cap or shell of the head, whereupon the cam pins ride up the tapered surfaces of the die carriers and so close the chasers and thus set the die for the next threading operation in a manner which will be readily understood.

Carried by the die spindle, between a collar 107 thereof and the grooved collar or spool 100, is a spiral spring 108, the purpose of which is to quickly pull back the die spindle as soon as the threading operation is completed and the die is opened. When the tool slide is moving toward the work spindles and the threading die has commenced to thread one of the rods this die travels on to the work faster than the tool slide moves; consequently the spring 108 is compressed, so that when the threading operation is completed and the die is opened this spring being under compression will immediately draw back the threading die spindle and thereby the threading die from the rod and

so permit the indexing of the turret. The spring, however, is not of sufficient force to close the die in readiness for another threading operation, and therefore the means hereinbefore described for this purpose, comprising the lever 101 and its coöperating parts, is provided.

From the foregoing it will be observed that by means of the present improvement each rod is successively brought into position to be threaded, at which time the rotation thereof is stopped by the friction clutch operating means, whereupon the rod is threaded by the threading die, which is continuously rotated in the same direction, and on the completion of such threading the die immediately opened and backed off, without the necessity of reversing the die or of starting up the work spindle for this purpose, thus very materially saving time, as it enables the work spindle to be immediately rotated through the operation of the friction clutch mechanism hereinbefore described and the turret quickly indexed to bring other rods into position to be operated upon. Thus in the present machine the necessity of backing off the die by reversing it, or rotating the work spindle, is avoided,—consequently saving the time required for this operation.

30 I claim as my invention:

1. In an automatic multiple spindle screw machine, the combination of a rotary turret carrying a series of rotary work carrying spindles, means for revolving said turret intermittently, means for rotating the work carrying spindles, means for holding each of the work carrying spindles stationary at a predetermined time in the revolution of the turret and during the threading operation, a sliding tool carrier, a threading die carried thereby, means for rotating said threading die continuously in the same direction, and means for closing and opening the die thereby to permit it to be backed off 45 from the work without rotating the work or reversing the threading die.

2. In an automatic multiple spindle screw machine, the combination of a rotary turret carrying a series of rotary work carrying spindles, means for revolving said turret intermittently, means for rotating the work carrying spindles, means for holding each of the work carrying spindles stationary at a predetermined time in the revolution of the turret and during the threading operation, a sliding tool carrier, a threading die carried thereby, means for rotating said threading die continuously in the same direction, means for opening the die thereby 60 to permit it to be backed off without rotating the work or reversing the threading die, and means for closing the die after the same is backed off in readiness for another threading operation.

65 3. In an automatic multiple spindle screw

machine, the combination of a rotary turret carrying a series of rotary work carrying spindles, means for revolving said turret intermittently, means for rotating the work carrying spindles, means for holding each of the work carrying spindles stationary at a predetermined time in the revolution of the turret and during the threading operation, a sliding tool carrier, a threading die carried thereby, means for rotating said threading die continuously in the same direction, means for closing and opening the die thereby to permit it to be backed off from the work without rotating the work or reversing the threading die, and means for accelerating the backing off of the die on the opening thereof.

4. In an automatic multiple spindle screw machine, the combination of a rotary turret carrying a series of rotary work carrying spindles, means for revolving said turret intermittently, means for rotating the work carrying spindles, means for holding each of the work carrying spindles stationary at a predetermined time in the revolution of the turret and during the threading operation, a sliding tool carrier, a shiftable spindle carried by the carrier, a threading die carried by the spindle, means for rotating said threading die continuously in the same direction, means for closing and opening the die thereby to permit it to be backed off from the work without rotating the work or reversing the threading die, and means for accelerating the backing off of the die on the opening thereof and comprising a spring mounted on the shiftable die-spindle.

5. In an automatic multiple spindle screw machine, the combination of a rotary turret carrying a series of rotary work carrying spindles, means for revolving said turret intermittently, means for rotating the work carrying spindles, means for holding each of the work carrying spindles stationary at a predetermined time in the revolution of the turret and during the threading operation, a sliding tool carrier, a threading die carried thereby and comprising a body and a head shiftable one relatively to the other, means for rotating said threading die continuously in the same direction, and means for shifting one of said parts of the die thereby to close and open the die to permit it to be backed off from the work without rotating the work or reversing the threading die, said die opening means comprising means shiftable with the sliding tool carrier.

6. In an automatic multiple spindle screw machine, the combination of a rotary turret carrying a series of rotary work carrying spindles, means for revolving said turret intermittently, means for rotating the work carrying spindles, means for holding each of the work carrying spindles stationary at a predetermined time in the revolution of the

- 8
- 6 turret and during the threading operation, a sliding tool carrier, a threading die carried thereby and comprising a body and a head one shiftable relatively to the other, means for rotating said threading die continuously in the same direction, and means for closing and opening the die thereby to permit it to be backed off from the work without rotating the work or reversing the threading die,
- 10 10 said die opening means comprising a lever in engagement with the die head, a shiftable shaft connected with said lever, a projection on said shaft and means adapted to engage said projection thereby to open the die.
- 15 7. In an automatic multiple spindle screw machine, the combination of a rotary turret carrying a series of rotary work carrying spindles, means for revolving said turret intermittently, means for rotating the work carrying spindles, means for holding each of the work carrying spindles stationary at a predetermined time in the revolution of the turret and during the threading operation, a sliding tool carrier, a threading die carried
- 20 20 thereby and comprising a body and a head shiftable one relatively to the other, means for rotating said threading die continuously in the same direction, and means for closing and opening the die thereby to permit it to be backed off from the work without rotating the work or reversing the threading die,
- 25 25 said die opening means comprising a lever in engagement with the die head, a shiftable shaft connected with said lever, an adjustable collar on said shaft and means adapted to engage said collar thereby to open the die.
- 30 8. In an automatic multiple spindle screw machine, the combination of a rotary turret carrying a series of rotary work carrying spindles, means for revolving said turret intermittently, means for rotating the work carrying spindles, means for holding each of the work carrying spindles stationary at a predetermined time in the revolution of the turret and during the threading operation, a sliding tool carrier, a threading die carried
- 35 35 thereby and comprising a body and a head shiftable one relatively to the other, means for rotating said threading die continuously in the same direction, and means for closing and opening the die thereby to permit it to be backed off from the work without rotating the work or reversing the threading die,
- 40 40 said die opening means comprising a lever in engagement with the die head, a shiftable shaft connected with said lever, a projection on said shaft and means adapted to engage said projection thereby to open the die.
- 45 9. In an automatic multiple spindle screw machine, the combination of a rotary turret carrying a series of rotary work carrying spindles, means for revolving said turret intermittently, means for rotating the work carrying spindles, means for holding each of the work carrying spindles stationary at a predetermined time in the revolution of the turret and during the threading operation, a sliding tool carrier, a threading die carried
- 50 50 thereby and comprising a body and a head shiftable one relatively to the other, means for rotating said threading die continuously in the same direction, and means for closing and opening the die thereby to permit it to be backed off from the work without rotating the work or reversing the threading die,
- 55 55 said die opening means comprising a lever in engagement with the die head, a shiftable shaft connected with said lever, a projection on said shaft, and means adapted to engage said projection thereby to open the die and comprising a pivoted lever and a cam for operating said lever.
- 60 10. In an automatic multiple spindle screw machine, the combination of a rotary turret carrying a series of rotary work carrying spindles, means for revolving said turret intermittently, means for rotating the work

carrying spindles, means for holding each of the work carrying spindles stationary at a predetermined time in the revolution of the turret and during the threading operation, a sliding tool carrier, a threading die carried thereby and comprising a body and a head shiftable one relatively to the other, means for rotating said threading die continuously in the same direction, and means for closing and opening the die thereby to permit it to be backed off from the work without rotating the work or reversing the threading die, said die closing means comprising means shiftable with the sliding tool carrier.

70 75 80 85 90 95 100 105 110 115 120 125

11. In an automatic multiple spindle screw machine, the combination of a rotary turret carrying a series of rotary work carrying spindles, means for revolving said turret intermittently, means for rotating the work carrying spindles, means for holding each of the work carrying spindles stationary at a predetermined time in the revolution of the turret and during the threading operation, a sliding tool carrier, a threading die carried thereby and comprising a body and a head shiftable one relatively to the other, means for rotating said threading die continuously in the same direction, and means for closing and opening the die thereby to permit it to be backed off from the work without rotating the work or reversing the threading die, said die closing means comprising a stop, a pivoted arm shiftable with the tool carrier and carrying a stop adapted to engage said first stop and thereby shift the die body.

110 115 120 125

12. In an automatic multiple spindle screw machine, the combination of a rotary turret carrying a series of rotary work carrying spindles, means for revolving said turret intermittently, means for rotating the work

- carrying spindles, means for holding each of the work carrying spindles stationary at a predetermined time in the revolution of the turret and during the threading operation, a sliding tool carrier, a threading die carried thereby and comprising a body and a head shiftable one relatively to the other, means for rotating said threading die continuously in the same direction, and means for closing and opening the die thereby to permit it to be backed off from the work without rotating the work or reversing the threading die, said die opening means comprising means carried by the sliding tool carrier and said die closing means also comprising means carried by the sliding tool carrier.

13. In an automatic multiple spindle screw machine, the combination of a rotary turret carrying a series of rotary work carrying spindles, means for revolving said turret intermittently, means for rotating the work carrying spindles, means for holding each of the work carrying spindles stationary at a predetermined time in the revolution of the turret and during the threading operation, a sliding tool carrier, a threading die carried thereby and comprising a body and a head shiftable one relatively to the other, means for rotating said threading die continuously in the same direction, and means for closing and opening the die thereby to permit it to be backed off from the work without rotating the work or reversing the threading die, said die opening means comprising means carried by the sliding tool carrier and said die closing means also comprising means carried by the sliding tool carrier, one operative on the head of the die and the other on the body thereof.

14. In an automatic multiple spindle screw machine, the combination of a rotary turret carrying a series of rotary work carrying spindles, means for revolving said turret intermittently, means for rotating the work carrying spindles, means for holding each of the work carrying spindles stationary at a predetermined time in the revolution of the turret and during the threading operation, a sliding tool carrier, a sliding spindle carried by said tool carrier, a threading die carried by said tool carrier and comprising a body and a head shiftable one relatively to the other, means for rotating said threading die continuously in the same direction, and means for closing and opening the die thereby to permit it to be backed off from the work without rotating the work or reversing the threading die, said die opening means comprising means carried by the sliding tool carrier and said die closing means also comprising means carried by the sliding tool carrier and operative on the threading die spindle.

15. In an automatic multiple spindle screw machine, the combination of a rotary turret carrying a series of rotary work carrying spindles, means for revolving said turret intermittently, means for rotating the work carrying spindles, means for holding each of the work carrying spindles stationary at a predetermined time in the revolution of the turret and during the threading operation, a sliding tool carrier, a sliding spindle carried by the tool carrier, a threading die carried by said tool carrier and comprising a body and a head shiftable one relatively to the other, means for rotating said threading die continuously in the same direction, and means for closing and opening the die thereby to permit it to be backed off from the work without rotating the work or reversing the threading die, said die opening means comprising a lever in engagement with the die head, a shiftable shaft connected with said lever and movable with the sliding tool carrier, a collar on said shaft and means adapted to engage said collar thereby to open the die, and said die closing means comprising an arm carried by the sliding tool carrier and coöperating with the threading die spindle, a stop carried thereby, and a stop adapted to be engaged by said last stop thereby to close the die.

16. In an automatic multiple spindle screw machine, the combination of a rotary turret carrying a series of rotary work carrying spindles, means for revolving said turret intermittently, means for rotating the work carrying spindles, means for holding each of the work carrying spindles stationary at a predetermined time in the revolution of the turret and during the threading operation, a sliding tool carrier, a sliding spindle carried by the tool carrier, a threading die carried thereby and comprising a body and a head shiftable one relatively to the other, means for rotating said threading die continuously in the same direction, and means for closing and opening the die thereby to permit it to be backed off from the work without rotating the work or reversing the threading die, said die opening means comprising a lever in engagement with the die head, a shiftable shaft connected with said lever and movable with the sliding tool carrier, a collar on said shaft, and means adapted to engage said collar thereby to open the die and comprising a pivoted lever and a cam for shifting said lever, and said die closing means comprising an arm carried by the sliding tool carrier and coöperating with the threading die spindle, a stop carried thereby, and a stop adapted to be engaged by said last stop thereby to close the die.

17. In an automatic multiple spindle screw machine, the combination of a rotary turret carrying a series of rotary work carrying spindles, means for revolving said turret intermittently, means for rotating the work carrying spindles, means for holding each of

the work carrying spindles stationary at a predetermined time in the revolution of the turret and during the threading operation, a sliding tool carrier, a sliding spindle carried by the tool carrier, a threading die carried thereby and comprising a body and a head shiftable one relatively to the other, means for rotating said threading die continuously in the same direction, means for 5 closing and opening the die thereby to permit it to be backed off from the work without rotating the work or reversing the threading die, said die opening means comprising a lever in engagement with the die 10 head, a shiftable shaft connected with said lever and movable with the sliding tool carrier, a collar on said shaft and means adapted to engage said collar thereby to open the die, and said die closing means comprising 15 an arm carried by the sliding tool carrier and coöperating with the threading die spindle, a stop carried thereby and a stop adapted to be engaged by said last stop thereby to close the die, and a spring carried by the 20 threading die spindle for accelerating the backing off of the die on the opening thereof.

18. In an automatic multiple spindle screw machine, the combination of a rotary 25 turret carrying a series of rotary work carrying spindles, means for revolving said turret intermittently, means for rotating the work carrying spindles, means for holding each of the work carrying spindles stationary at a predetermined time in the revolution 30 of the turret and during the threading operation, a sliding tool carrier, a sliding spindle carried by the tool carrier, a threading die carried thereby and comprising a 35 body and a head shiftable one relatively to the other, means for rotating said threading die continuously in the same direction, means for closing and opening the die thereby to permit it to be backed off from the work 40 without rotating the work or reversing the threading die, said die opening means comprising a lever in engagement with the die head, a shiftable shaft connected with said lever and movable with the sliding tool carrier, a collar on said shaft, and means adapted 45 to engage said collar thereby to open the die and comprising a pivoted lever and a cam for shifting said lever, said die closing means comprising an arm carried by the 50 sliding tool carrier and coöperating with the threading die spindle, a stop carried thereby and a stop adapted to be engaged by said last stop thereby to close the die, and a spring carried by the threading die spindle 55 for accelerating the backing off of the die on the opening thereof.

19. In an automatic multiple spindle screw machine, the combination of a rotary 60 turret carrying a series of rotary work carrying spindles, means for revolving the tur-

ret intermittently, means for rotating each of the work carrying spindles in the same direction, means for holding each of the work carrying spindles stationary during the threading operation, a sliding tool carrier carrying a plurality of tools one comprising an openable and closable threading die, means for rotating the threading die continuously in one direction, and means for 70 opening and closing the die thereby to enable it to be backed off from the work without rotating the work or reversing the threading die.

20. In an automatic multiple spindle screw machine, the combination of a rotary 75 turret carrying a series of rotary work carrying spindles, means for revolving said turret intermittently, means for rotating the work carrying spindles, means for holding each of the work carrying spindles stationary at a predetermined time in the revolution of the turret and during the threading operation and comprising a clutch carried by each of said work spindles and an actuator for successively engaging 80 each of said clutches thereby to operate it, a sliding tool carrier, a threading die carried thereby, means for rotating said threading die continuously in the same direction, and means for closing and opening the die 85 thereby to permit it to be backed off from the work without rotating the work or reversing the threading die.

21. In an automatic multiple spindle screw machine, the combination of a rotary 90 turret carrying a series of rotary work carrying spindles, means for revolving the turret intermittently, means for rotating each of the work carrying spindles in the same direction, a clutch carried by each of the 95 work spindles, means for operating each of the clutches at a predetermined time thereby to stop the rotation of its spindle, means for holding the spindle stationary during the threading operation, a sliding tool carrier 100 carrying a plurality of tools, one comprising an openable and closable threading die comprising a head and a body shiftable one relatively to the other, a sliding spindle carrying said die, means for rotating the 105 threading die continuously in one direction, means for opening and closing the die thereby to enable it to be backed off from the work without rotating the work or reversing the threading die, said die opening means 110 comprising cam operated means and said die closing means comprising stop operated means, and means carried by the spindle for accelerating the backing off of the die on the 115 opening thereof.

22. In a machine of the class described, the combination of a work carrying spindle supported for rotary movement in one direction, means for rotating said spindle, means for stopping and holding the spindle sta- 120 125

- tionary during the threading operation, a shiftable and rotatable threading die supported in position to operate on the work carried by the work carrying spindle, means for rotating said threading die continuously in the same direction, and means for opening and closing the die thereby to permit it to be backed off from the work without rotating the work or reversing the threading die.
- 5 23. In a machine of the class described, the combination of a work carrying spindle supported for rotary movement in one direction, means for rotating said spindle, means for stopping and holding the spindle station-
- 10 ary during the threading operation, a shift-
- 15

able and rotatable threading die supported in position to operate on the work carried by the work carrying spindle, means for rotating said threading die continuously in the same direction, means for opening and closing the die thereby to permit it to be backed off from the work without rotating the work or reversing the threading die, means for backing off the die from the work, and means for accelerating during such backing off movement the backing off of the die.
